UNITED STATES PATENT OFFICE.

ALFRED RUSSELL SCOTT, OF ENID, OKLAHOMA.

CUTTING-TOOL.

1,341,482.

Specification of Letters Patent.

Patented May 25, 1920.

Application filed April 12, 1919. Serial No. 289,507.

To all whom it may concern:

Be it known that I, ALFRED RUSSELL SCOTT, a citizen of the United States, residing at Enid, in the county of Garfield and State of 5 Oklahoma, have invented certain new and useful Improvements in Cutting-Tools, of which the following is a specification, reference being had to the accompanying drawings.

10 This invention relates to certain improvements in cutting tools and has relation more particularly to a device of this general character especially designed and adapted for use in the truing of crank pins and crank 15 shafts of internal combustion engines or the like, and it is an object of this invention to provide a device of this general character having novel and improved means whereby the same may be readily and conveniently 20 arranged upon the work and which operates to properly form such work upon rotation of the tool.

A further object of the invention is to provide a novel and improved device of this 25 general character adapted to be mounted upon and rotate around the work to be cut and wherein the tool comprises a cutting member adjustable relative to the work.

Another object of the invention is to provide a novel and improved tool of this character comprising two separable sections 30 adapted to be disposed around the crank pin or other work and which are connected for unitary movement about the work and 35 wherein one of the sections is provided with a cutting tool for engagement with the work.

An additional object of the invention is to provide a novel and improved device of this 40 general character having means to permit the clearance of the shavings resulting from a cutting operation and wherein means are also provided whereby the cutting member may be conveniently lubricated.

The invention consists in the details of 45 construction and in the combination and arrangement of the several parts of my improved cutting tool whereby certain important advantages are attained and the device rendered simpler, less expensive and otherwise 50 more convenient and advantageous for use, as will be hereinafter more fully set forth.

The novel features of my invention will hereinafter be definitely claimed.

55 In order that my invention may be the

better understood, I will now proceed to describe the same with reference to the accompanying drawings, wherein:

Figure 1 is a view in perspective of a cutting tool constructed in accordance with an 60 embodiment of my invention.

Fig. 2 is an enlarged sectional view taken through my improved tool as herein embodied and on a line substantially at right angles to the recesses in the opposed faces 65 of the sections of the tool.

Fig. 3 is a sectional view taken substantially on the line 3—3 of Fig. 2 with my improved tool shown in applied position upon a crank shaft. 70

Fig. 4 is a fragmentary sectional view taken substantially on the line 4—4 of Fig. 2.

Fig. 5 is a view in perspective of the cutting member as herein embodied, and

Fig. 6 is a view in perspective of the 75 wedge member herein employed for coaction with the cutting member.

As disclosed in the accompanying drawings, my improved tool comprises two sections A and B adapted one to overlie the 80 other and which sections are preferably angular in section so that when the sections A and B are assembled, a monkey wrench or other tool may be engaged therewith to impart the requisite rotation thereto. 85

The opposed faces of the sections A and B have extending entirely thereacross the registering recesses 1 and 2, respectively, and each of which is substantially semi-circular in form and of a radius so that the 90 sections A and B will snugly fit upon a crank pin, crank shaft or other work with which the same is employed.

The sections A and B are maintained in assembled relation through the medium of 95 the studs 3 secured to the section A at opposite sides of the recess 1 therein. The studs 3 are of a length to extend through the openings 4 formed in the section B at opposite sides of the recess 2 therein and to extend 100 beyond such section B when the sections A and B are in assembled relation. Threaded upon the extended portions of the studs 3 are the clamping nuts 5.

The wall of the recess 2 in the section B to 105 one side of its center is provided with a groove or channel 6 having its side walls a straight and in parallelism and with its bottom wall b flat and disposed on a slight incline from one end to the other. In com- 110

munication with the groove or channel 6 substantially midway thereof is an opening 7 disposed through the outer portion of the section B and for a purpose which will be 5 hereinafter more particularly referred to.

The wall of the recess 2 of the section B immediately adjacent the groove or channel 6 is provided with a shallow channel 8 extending entirely therewith and which 10 serves to afford a discharge to permit the desired clearance of the shavings produced during a cutting or working operation. This channel 8 also has in communication therewith the openings or ports 9 extending 15 through the outer portion of the section B to afford means for delivering oil or other lubricant to the cutting member M to facilitate its function.

The cutting member M snugly fits between the walls *a* and *b* of the groove or channel 6 and has its outer or working face transversely rounded on substantially the same radius as the recess 2 and the high longitudinal edge *c* of such face of the cutting member M constitutes a knife edge 25 to operate upon the work.

Interposed between the wall *b* of the groove or channel 6 is the wedge 10 which, upon longitudinal movement thereof, operates to adjust the member M, or more particularly the cutting edge *c* thereof, relative to the work as the occasions of practice may require.

Carried by the inner face of the member 35 M substantially centrally thereof is an outstanding stud 11 which extends through the longitudinally disposed slot 12 formed in the wedge 10 and through the opening 7 in the section B. The stud 11 terminates exteriorly of the section B and has threaded thereupon the clamping nut 14 so that the member M may be held in its desired adjustments toward or from the work.

A bearing C is provided for the reception 45 of the crank pin (not shown) and this bearing has rounded portions X at its opposite ends, and in order to compensate for this formation, the ends of the working face of the member M, together with the ends of 50 the recesses 2, are correspondingly rounded, as indicated at 15. The section A is provided with an enlarged opening 16 in communication with and preferably at right angles to the recess 1 therein, and this opening 55 16 permits visual access to the work during an operation so that it can be readily determined when a cutting operation has been completed or the bearing turned true.

From the foregoing description, it is 60 thought to be obvious that a cutting tool constructed in accordance with my invention is particularly well adapted for use by reason of the convenience and facility with

which it may be assembled and operated, and it will also be obvious that my invention is 65 susceptible of some change and modification without departing from the principles and spirit thereof and for this reason I do not wish to be understood as limiting myself to the precise arrangement and formation of 70 the several parts herein shown in carrying out my invention in practice except as hereinafter claimed.

I claim:

1. In a cutting tool, the combination with 75 a body comprising a pair of separable members arranged one upon the other, the opposed faces of said members having registering semi-circular recesses extending thereacross to receive the work, the wall of the 80 recess of one member at one side of its transverse center being provided with a channel extending longitudinally thereof, said wall of the recess at the opposite side of its transverse center being provided with a longitudinally disposed clearance channel semi-circular in cross section, the first channel being rectangular in cross section, of a cutting tool 85 rectangular in cross section adjustably mounted in the rectangular channel and 90 provided with parallel cutting edges, said cutting tool being removably reversible in the rectangular channel, whereby either of its cutting edges may coincide with the longitudinal center of the semi-circular recess of said wall, and means for holding the 95 two members in assembled relation.

2. In a cutting tool, the combination with 100 a body comprising two separable members arranged one upon the other, the opposed faces of said member having registering recesses extending transversely thereacross to receive the work, the wall of the recess of 105 one member having a longitudinal channel rectangular in cross section, of a cutting tool rectangular in cross section, removably reversible in said rectangular channel, said cutting tool being adjustably fixed in said channel and provided with parallel longitudinal cutting edges, said rectangular channel 110 being formed in said wall at one side of its transverse center, whereby the tool may be reversed so that either one of its cutting edges may coincide with the transverse center of the wall of said recesses, said wall 115 having a clearance channel semi-circular in cross section at the opposite side of its transverse center of the wall, and means for holding the members in assembled relation.

In testimony whereof I hereunto affix my 120 signature in the presence of two witnesses.

ALFRED RUSSELL SCOTT.

Witnesses:

H. N. BOARDMAN,
MABEL MORRIS.
